DESIGN FOR A COMBINED SMOKING STAND AND LIGHTER

Charles W. Beeston, New York, N. Y.

Application June 19, 1935, Serial No. 57,335

Term of patent 3½ years

To all whom it may concern:

Be it known that I, Charles W. Beeston, a citizen of the United States, residing at New York, in the county and State of New York, have invented a new, original, and ornamental Design for a Combined Smoking Stand and Lighter, of which the following is a specification, reference being had to the accompanying drawing, forming part thereof, in which the figure is a perspective view of a combined smoking stand and lighter, showing my new design.

I claim:

The ornamental design for a combined smoking stand and lighter, as shown.

CHARLES W. BEESTON.
